CLAIM

The ornamental design for a mobile computer, as shown in the accompanying drawings and described above.

DESCRIPTION

FIG. 1 is a top, rear, left perspective view of a mobile computer in accordance with the present invention.

FIG. 2 is a bottom, front, left perspective view of the mobile computer of FIG. 1;

FIG. 3 is a bottom, front, right perspective view of the mobile computer of FIG. 1;

FIG. 4 is a top plan view of the mobile computer of FIG. 1; FIG. 5 is a bottom plan view of the mobile computer of FIG. 1;

FIG. 6 is a right elevation view of the mobile computer of FIG. 1;

FIG. 7 is a left elevation view of the mobile computer of FIG. 1;

FIG. 8 is a rear elevation view of the mobile computer of FIG. 1; and,

FIG. 9 is a front elevation view of the mobile computer of FIG. 1.

The broken lines shown herein are for illustrative purposes and form no part of the claimed design.

1 Claim, 7 Drawing Sheets
